DECORATIVE MOLDING STRIP

John R. Morgan, Wheeling, Ill., assignor to Amerock Corporation, Rockford, Ill., a corporation of Connecticut

Filed Jan. 30, 1967, Ser. No. 5,600

Term of patent 14 years

(Cl. D13—6)

FIGURE 1 is a front view of the decorative molding strip incorporating my new design.

FIG. 2 is a top view of the molding strip.

FIG. 3 is an enlarged fragmentary perspective view of the strip.

FIG. 4 is an enlarged sectional view taken along the line 4—4 in FIG. 2.

I claim:

The ornamental design for a decorative molding strip, as shown.
